Radio Corporation of America, a corporation
of Delaware

Application February 28, 1939, Serial No. 259,069

8 Claims. (Cl. 173—44)

This invention relates to coupling devices, and more particularly to means for increasing the width of the frequency characteristic of coupling transformers or the like.

The use of a quarter wave resonant line as an impedance inverter is well known. Such a line has uniformly distributed inductance and capacity. Its input impedance is inductive at frequencies on one side of resonance, capacitive at frequencies on the other side of resonance, and resistive at the resonant frequency, where the resonant frequency is that frequency at which the length of each conductor is a quarter wave. If such an inverter is connected to a modulated carrier source, it presents to the carrier source a resistive impedance, and to all side band frequencies its impedance is reactive.

It is usually desirable to keep the reactance of a circuit constant throughout the frequency range of the applied voltage. It previously has been the custom to accomplish this to a limited extent by loading the resonant circuit with a certain amount of resistance to decrease the sharpness of the resonance curve. This method, however, introduces excessive losses in the circuit, and is not entirely satisfactory.

It is, therefore, the primary object of this invention to provide a transformer which efficiently couples devices of different impedance without introducing losses and which presents a uniform impedance to each device over a wide range of frequencies. This invention will be better understood from the following description when considered in connection with the accompanying drawing, in which Figure 1 represents a single quarter wave resonant line; Figure 2 is the reactance curve of the resonant line of Fig. 1; Figure 3 is a transformer made in accordance with this invention; Figure 4 is the reactance curve of the resonant line combination of Fig. 3; and Figure 5 is an illustration to aid in the theoretical discussion.

Referring to Fig. 1, R_0 is the impedance of an output device 0 which is to be matched to the impedance R_1 of an input device 1. These impedances may, of course, represent the impedance of a transmission line, antenna, vacuum tube, or any other radio device. To provide proper matching, the impedance R_0 must be converted to an impedance R_1 . While the function of the quarter wave line in this connection is well known, it is to be understood that this invention is not limited to a quarter wave transmission line impedance inverter. The equivalent circuit which consists of a plurality of inductors and capacitors

connected to form a plurality of T sections, for example, may be substituted. In addition, while the physical length of the quarter wave line will theoretically be equal to one quarter of the resonant wave length, it must be understood that the line characteristics may be influenced by inductive or capacitive loads, in which case the actual length of the line will have to be adjusted to restore the circuit to resonance.

If Z_0 is the characteristic impedance of the transmission line of Fig. 1, its value at the resonant frequency f_0 may be expressed in the following terms:

$$Z_0^2 = R_0 R_1 \quad (1)$$

Curve X of Fig. 2 illustrates the variations in the reactance of the transmission line of Fig. 1 when the frequency is varied between zero and twice the resonant frequency. Curve R represents the pure resistance component of the line between the same frequency limits.

It is to be noted that at zero frequency the input impedance is equal to R_0 , and the reactance is zero. Likewise, at $2f_0$, at which frequency each conductor is one-half wave length long, the reactance is zero and the input impedance is again equal to R_0 . At f_0 , however, while the reactance is zero, the resistance has been reduced to a value R_1 which depends on the ratio of transformation of the line.

As noted above, the rapid change of impedance of a quarter wave line is not always desirable. The slope of the curve X of Fig. 2 at the frequency f_0 is a measure of the rate of change of impedance. It is the purpose of this invention to make the slope of the curve zero at frequency f_0 as shown in Fig. 4. In such a case the derivative of the curve X at the point f_0 would equal zero, that is,

$$\frac{dX}{df_0} = 0 \quad (2)$$

Referring to Fig. 3, a transformer is shown in accordance with this invention which fulfills the conditions of Equation 2 when the mid-impedance, Z_m , is related to the output impedance R_0 and the input impedance R_1 as follows:

$$Z_m = \sqrt{R_0 R_1} \quad (3)$$

That is, the mid-impedance is made equal to the geometric mean of the input and output impedances. To accomplish this, the dimensions of the conductors and their relative spacings are adjusted until the desired relation is obtained.

By analogy to Equation 1 the equations for the

characteristic impedances of the respective transmission lines of Fig. 3 will be

$$Z_0^2 = R_0 Z_m \quad (4)$$

and

$$Z_1^2 = R_1 Z_m \quad (5)$$

from which it follows that:

$$Z_0 = \sqrt{R_0 \sqrt{R_0 R_1}} \quad (6)$$

and

$$Z_1 = \sqrt{R_1 \sqrt{R_0 R_1}} \quad (7)$$

The proof that a transformer consisting of a plurality of serially connected quarter wave sections in which the mid-impedance is equal to the geometric mean of the input and output impedances has a flat reactance characteristic at the resonant frequency will now be given.

Referring to Fig. 5, a general equation for the impedance Z_{AB} looking into terminals A—B when disconnected from C—D is:

$$Z_{AB} = \left(\frac{R_0 \cos Ka + j Z_0 \sin Ka}{Z_0 \cos Ka + j R_0 \sin Ka} \right) \times Z_0 \quad (8)$$

where a is the line length, and

$$K = \frac{2\pi}{\lambda} \quad (9)$$

If then the impedance Z_{AB} is considered as the load across the terminals C—D, then the impedance Z_{EF} looking into terminals E—F becomes:

$$Z_{EF} = \left(\frac{Z_{AB} \cos Ka + j Z_1 \sin Ka}{Z_1 \cos Ka + j Z_{AB} \sin Ka} \right) Z_1 \quad (10)$$

and substituting the value of Z_{AB} from (8)

$$Z_{EF} = \left[\frac{\left(\frac{R_0 \cos Ka + j Z_0 \sin Ka}{Z_0 \cos Ka + j R_0 \sin Ka} \right) Z_0 \cos Ka + j Z_1 \sin Ka}{Z_1 \cos Ka + j Z_0 \sin Ka \left(\frac{R_0 \cos Ka + j Z_0 \sin Ka}{Z_0 \cos Ka + j R_0 \sin Ka} \right)} \right] Z_1 \quad (11)$$

Dividing the numerator and the denominator by the term $Z_0 \cos Ka + j R_0 \sin Ka$, and collecting terms

$$Z_{EF} = \frac{Z_1 [(R_0 Z_0 \cos^2 Ka - Z_1 R_0 \sin^2 Ka) + j (Z_0^2 + Z_0 Z_1) \sin Ka \cos Ka]}{Z_0 (Z_1 \cos^2 Ka - Z_0 \sin^2 Ka) + j R_0 (Z_1 + Z_0) \sin Ka \cos Ka} \quad (12)$$

This expression is seen to be in the form

$$\frac{a+jb}{c+jd} \quad (13)$$

which may be rationalized

$$\frac{(a+jb)(c-jd)}{(c+jd)(c-jd)} = \frac{(a+jb)(c-jd)}{c^2 + d^2} \quad (14)$$

The reactive component X may be obtained by selecting from (12) terms corresponding to

$$X_{EF} = \frac{bc - ad}{c^2 + d^2} \quad (15)$$

and the resistive component R may be obtained by selecting from (12) terms corresponding to

$$R_{EF} = \frac{ac + bd}{c^2 + d^2} \quad (16)$$

Thus:

$$X_{EF} = \frac{Z_1 \{ Z_0^2 (Z_0 + Z_1) \sin Ka \cos Ka \cos (Z_1 \cos^2 Ka - Z_0 \sin^2 Ka) - R_0^2 (Z_1 + Z_0) \sin Ka \cos Ka (Z_0 \cos^2 Ka - Z_1 \sin^2 Ka) \}}{Z_0^2 (Z_1 \cos^2 Ka - Z_0 \sin^2 Ka)^2 + R_0^2 (Z_1 + Z_0)^2 \sin^2 Ka \cos^2 Ka} \quad (17)$$

and when $Ka = 90^\circ$ the denominator above reduces Z_0^4 and the numerator reduces to 0, that is, as shown in Figs. 2 and 4, the reactance is zero at the frequency f_0 at which the lines are each a quarter wavelength long.

For simplicity, calling the numerator of (17) N and the denominator D , then

$$X_{EF} = \frac{N}{D} \quad (18)$$

and

$$\frac{d(X_{EF})}{d(Ka)} = \frac{DN^1 - ND^1}{D^2} \quad (18)$$

where N^1 and D^1 represent, respectively, the first derivatives of the numerator and the denominator.

Performing this operation, and evaluating at $Ka = 90^\circ$

$$N^1 = -(R_0^2 Z_1 - Z_0^3)(Z_0 + Z_1) \quad (19)$$

and since $N = 0$ when $Ka = 90^\circ$

$$\frac{d(X_{EF})}{d(Ka)} = \frac{-(R_0^2 Z_1 - Z_0^3)(Z_0 + Z_1)}{Z_0^4} \quad (20)$$

The desired condition that the slope of the reactance curve be equal to zero at the operating wave length is satisfied when the derivative is zero. To satisfy this condition it is necessary that

$$R_0^2 Z_1 - Z_0^3 = 0 \quad (21)$$

thus

$$R_0^2 Z_1 = Z_0^3 \text{ or } R_0^4 Z_1^2 = Z_0^6 \quad (22)$$

therefore

$$Z_1^2 = Z_0^6 / R_0^4 \quad (23)$$

and since when $Ka = 90^\circ$

$$\frac{Z_0^2}{R_0} = \frac{Z_1^2}{R_1} \quad (24)$$

55 by substituting the value of Z_1^2 in Equation 23 we obtain

$$\frac{R_1 Z_0^2}{R_0} = \frac{Z_0^6}{R_0^4} \quad (25)$$

from which it is apparent that

$$Z_0^4 = R_1 R_0^3 \quad (26)$$

$$Z_0^2 = R_0 \sqrt{R_1 R_0} \quad (27)$$

and

$$Z_0 = \sqrt{R_0 \sqrt{R_1 R_0}} \quad (28)$$

and likewise by substituting the value of Z_0^2 from Equation 24 in Equation 23 there is obtained

$$Z_1 = \sqrt{R_1 \sqrt{R_0 R_1}} \quad (29)$$

It has therefore been shown that when two

quarter wave resonant lines are connected in series, and when their respective characteristic impedances are related to the input and output impedances R_0 and R_1 in the manner shown by Equations 28 and 29, then the reactance of the transformer looking into the terminals E—F will be substantially independent of the applied frequency throughout a range on either side of the exact resonant frequency. This must be so since the slope of the reactance curve is zero at this point.

Fig. 4 illustrates the reactance and resistance characteristics which are obtained by the transformer shown in Fig. 3. As before, the reactance is zero at f_0 and $2f_0$, while the resistance at zero and $2f_0$ is equal to the output resistance R_0 . However, the resistance is low over a wider frequency range than before. As an example of the efficiency of this system, if f_0 is taken to be 90 megacycles, the reactance would be substantially zero throughout a range extending from 60 to 120 megacycles. It is also important to note that this result has been accomplished without loss of power. The full input energy is therefore available at the output.

For a still wider response characteristic, more quarter wave sections may be added, provided their respective characteristic impedances are related to the mid-impedance by the geometric mean. Thus, if four sections are used, a similar solution which includes determining the second derivative will show that the four characteristic impedances will be

$$Z_0 = \sqrt{R_0 \sqrt{R_0 R_1}} \quad (30)$$

$$Z_1 = \sqrt{\sqrt{R_0 R_1} \cdot \sqrt{R_0 \sqrt{R_0 R_1}}} \quad (31)$$

$$Z_2 = \sqrt{\sqrt{R_0 R_1} \cdot \sqrt{R_1 \sqrt{R_0 R_1}}} \quad (32)$$

$$Z_3 = \sqrt{R_1 \sqrt{R_1 \sqrt{R_0 R_1}}} \quad (33)$$

where, as before R_0 is the impedance of the source and R_1 is the impedance looking into the transformer network.

In this instance, by setting the second derivative equal to zero, the condition is imposed that the rate of change of the slope of the reactance curve is zero on either side of the resonant frequency.

To obtain a physical concept of the operation of this invention, consider the effect of changing the frequency of the applied voltage so that the quarter wave lines are no longer exactly resonant. From Fig. 2 it is apparent that the input impedance immediately becomes reactive. Suppose, for example, the frequency is changed so that a given inductive impedance is present at the terminals A—B of Fig. 5. The second quarter wave line is an impedance inverter, and consequently the impedance looking into the terminals E—F now becomes capacitive. However, the second line is also off resonance, so that it, too, adds an inductive component, which cancels a portion of the capacitive reactance. Thus the magnitude of the reactance has decreased by the action of the second serially connected quarter wave line. Additional sections increase this effect, but for practical purposes the additional advantage is more than offset by the additional cost, so that it is generally preferable to limit the transformer to the minimum number of sections which will provide the necessary band width.

I have thus described a coupling transformer

which consists of a plurality of serially connected quarter wave sections each having a different characteristic impedance which, when properly related to the input and output impedances, provides a substantially flat frequency vs. reactance characteristic for frequencies on either side of the normal resonant frequency of the sections.

I claim as my invention:

1. A coupling system for transferring energy between an output device having a terminal impedance R_0 and an input device having an input impedance R_1 which includes two circuits connected in series between said output and input devices, said circuits having characteristic impedances which are respectively satisfied by the equations:

$$Z_0 = \sqrt{R_0 \sqrt{R_0 R_1}}$$

$$Z_1 = \sqrt{R_1 \sqrt{R_0 R_1}}$$

where Z_0 is the characteristic impedance of the circuit connected to the output device and Z_1 is the characteristic impedance of the circuit connected to the input device.

2. A coupling system for transferring energy between an output device and an input device which includes two quarter wave transmission lines connected in series between said devices, said transmission lines having characteristic impedances respectively satisfied by the equations:

$$Z_0 = \sqrt{R_0 \sqrt{R_0 R_1}}$$

and

$$Z_1 = \sqrt{R_1 \sqrt{R_0 R_1}}$$

where

R_0 is the terminal impedance of said output device;

R_1 is the terminal impedance of said input device; Z_0 is the characteristic impedance of the transmission line connected to said output device; and

Z_1 is the characteristic impedance of the transmission line connected to said input device.

3. A coupling transformer adapted to connect an output device and an input device which includes two circuits connected in series, said circuits having characteristic impedances which are of such a value that the mid-impedance is equal to the geometric mean of the output and input impedances.

4. A coupling transformer adapted to connect an output device and an input device, said transformer including a plurality of serially connected circuits, said circuits having characteristic impedances of such a value that the mid-impedance is equal to the geometric mean of the output and input impedances.

5. A coupling transformer adapted to connect an output device and an input device, said transformer comprising four circuits connected in series, said circuits having characteristic impedances which are respectively satisfied by the equations:

$$Z_0 = \sqrt{R_0 \sqrt{R_0 \sqrt{R_0 R_1}}}$$

$$Z_1 = \sqrt{\sqrt{R_0 R_1} \sqrt{R_0 \sqrt{R_0 R_1}}}$$

$$Z_2 = \sqrt{\sqrt{R_0 R_1} \sqrt{R_1 \sqrt{R_0 R_1}}}$$

$$Z_3 = \sqrt{R_1 \sqrt{R_1 \sqrt{R_0 R_1}}}$$

where

Z_0 is the characteristic impedance of the circuit to be connected to the output impedance;
 Z_1 and Z_2 are the respective characteristic impedances of intermediate circuits;
 Z_3 is the characteristic impedance of the circuit to be connected to the input impedance;
 R_0 is the output impedance; and
 R_1 is the input impedance.

6. A coupling transformer having a wide band frequency characteristic for coupling an output device and an input device, said transformer comprising n serially connected circuits whose characteristic impedances are such that the mid-impedance is equal to the geometric mean of the impedance of the input and output devices, and in which the characteristic impedance of any circuit is equal to the geometric mean of the impedances of the adjacent circuits, where n is any even number.

7. A coupling transformer having a wide band frequency characteristic for coupling an input device and an output device, said transformer

comprising n serially connected quarter wave matching sections whose respective characteristic impedances are chosen so that the mid-impedance of said transformer is equal to the geometric mean of the impedances of the input and output devices, and in which the characteristic impedance of any section is equal to the geometric mean of the impedances of the adjacent sections, where n is any even number.

8. A transformer for coupling a first device and a second device, the impedances of said devices being matched over a wide band of frequencies, said transformer comprising n serially connected quarter wave sections, the characteristic impedance Z_m of any section being equal to

$$Z_m = R_1 \frac{2m-1}{2n} \times R_0^{1-\frac{(2m-1)}{2n}}$$

where

R_0 is the impedance of said first device, R_1 is the impedance of said second device, m is the number of the section Z_m , counted from the first device, and n is any even number.

GEORGE H. BROWN.
